UNITED STATES PATENT OFFICE.

NATHANIEL BOWDITCH, OF AURORA, ILLINOIS.

COTTON-PICKING MACHINE.

1,119,795.

Specification of Letters Patent. Patented Dec. 8, 1914.

Application filed October 6, 1905. Serial No. 281,592.

To all whom it may concern:

Be it known that I, NATHANIEL BOWDITCH, a citizen of the United States, residing at Aurora, in the county of Kane and State of Illinois, have invented a certain new and useful Improvement in Cotton-Picking Machines, of which the following is a specification.

My invention relates to cotton picking machines and has for its object to provide a new and improved device for picking cotton from the plants.

Referring to the accompanying drawings wherein I have illustrated my invention, Figure 1 is a plan view of a machine embodying the invention; Fig. 2 is an enlarged sectional view showing a portion of one of the wheels of the machine; Fig. 3 is an enlarged elevation with parts cut away showing the exterior faces of one of the wheels of the machine; Fig. 4 is a sectional view taken on line 4—4 of Fig. 2; Fig. 5 is a view showing the cam slot on the hub of one of the wheels; Fig. 6 is a view showing the cam slot flattened out; Fig. 7 is a sectional view showing one of the guides for the pickers; Fig. 8 is an exterior view of the guide of Fig. 7; Fig. 9 is a sectional view taken on line 9—9 of Fig. 7; Fig. 10 is a sectional view taken on line 10—10 of Fig. 8; Fig. 11 is a view of one of the engaging devices through which the pickers pass; Fig. 12 is a view of the flanged disk which forms a guide for the actuating parts.

Like letters refer to like parts throughout the several figures.

Referring now to the drawings, I have shown in Fig. 1 one form of cotton picking device embodying my invention. This device is provided with two wheels A, having a space between them. The machine is drawn along the ground so that the row of cotton plants come between the two wheels, one wheel being on each side thereof. These wheels are mounted upon an axle A¹ upon which they rotate. A series of spiral cotton picking devices B are associated with each wheel, said picking devices passing through guides B¹ attached to the wheel, said guides being shown more in detail in Fig. 7. These pickers are provided with flexible picker points B² which project laterally therefrom and which engage the cotton when the pickers are rotated so as to cause it to be wound about such pickers. The ends of these pick-

ers are connected to bars C, there being a series of these bars extending around the wheel, as shown in Fig. 3. The pickers are rotatably mounted in these bars in any desired manner. The bars C are held in position by any desired means, as for example by the rods C¹, and are moved back and forth along said rods so as to push the pickers in and out through the guides. This movement of the pickers causes them to rotate about their axis. The picker bars C are moved back and forth by means of the levers D, which are fastened to the bars in any desired manner. As herein shown, these levers are bifurcated and fastened to the bars by means of holding pieces D¹ which pass through the bars, the levers being slotted, as at D², to receive them. This permits the levers to move with relation to the bars.

The hub A² of the wheel is provided with a groove A³ extending completely therearound, see Fig. 4, and the ends of the levers D fit into this groove, the ends being rounded so that the levers can rock back and forth. Each lever is preferably provided with a projection D⁴, adapted to be engaged by a cap piece D⁴ attached to the hub of the wheel so as to hold the lever in place. The cap D⁴ is cut away as shown to permit the free rocking of the lever and is removably held in place by the screws D⁵. These screws are made long as shown so as to project away from the center and to a point where their ends are accessible. It will thus be seen that each of the levers D is provided with a holding piece D⁴ which prevents the levers from being withdrawn from the groove A³. Connected with each of these levers between its ends, is an actuating piece E, the connection being a slotted connection to permit relative movement between them. Each actuating piece is provided with a projecting part E¹, which is preferably a roller, and which passes between two guiding devices F and F¹, the guiding devices arranged so as to form a cam slot E² into which the projections E¹ extend. The parts F and F¹ are fastened in any suitable manner, as by means of bolts, to the cylindrical part F², which is mounted upon a sleeve F³ having a projecting flange F⁴, the sleeve being keyed or otherwise fixed to the axle A¹. A bolt or pin F⁵ passes through this sleeve and enters an opening in the axle so as to prevent the

sleeve from being moved longitudinally. The cylindrical supporting device F^3 for the guiding pieces F and F^1 is fastened to the flange F^5 by means of bolts F^6 , the bolts being screw-threaded into the flange and passing through slotted openings in the support F^2 so that by loosening the bolts the support F^3 may be partially rotated about the axle so as to vary the position of the cam slot and the guiding parts F and F^1 . By arranging the guiding devices F and F^1 so as to make the cam slot change in direction, it will be seen that the actuating device E and the lever D and the bar C and associated pickers can be moved back and forth so as to thrust the pickers through the wheel and cause them to engage the cotton on the plants and then withdraw them into the wheel, so as to wipe off the cotton which has become wrapped thereabout because of their rotary movement. In view of the fact that the machine is moving forward, the pickers are in contact with the cotton plants only a short time and it is, therefore, desirable to cause the pickers to rotate rapidly while this contact is being made. This result is secured by arranging the guiding devices so as to give the cam slot the proper shape. The pickers should be thrust out when they are near the ground. I also interpose between the pickers and the actuating piece what may be called a multiplying device or mechanism, which multiplies the movement of the pickers, and which is arranged so as to be brought into operation at the time when the pickers are in contact with the cotton bolls, thus giving the pickers a comparatively high speed of rotation at this time when such rotation is so desirable and necessary. It is of course evident that various mechanisms or devices may be used for this purpose, and I have only attempted to show a simple construction. It will be seen that the movement of the actuating piece E is multiplied so as to increase the movement of the pickers resulting therefrom.

Referring now to Fig. 6, which shows the guiding devices and the cam slot developed or flattened out, it will be noted that this cam slot is straight a portion of its length and is then given a sharp incline. When, for example, the rollers of the actuating devices are located in the cam slot at the point E^3 , the pickers are entirely drawn within the wheel and guides. As the roller moves along the straight portion of the slot, there is no outward movement of the pickers. When the roller reaches the point E^4 , there is an incline in the guides and slot to the point E^5 . This throws the pickers out a portion of their length and the cam is in such position that this occurs as the pickers approach the ground. From the point E^5 to the point E^6 there is a sharp incline and the pickers are during this portion of the rotation forced rapidly outward and thus given a rapid rotation and the cams are arranged so that this occurs when the pickers are in the most effective contact with the cotton plant. From the point E^6 to the point E^7 the sharp incline is in the opposite direction, thus causing the pickers to be rapidly withdrawn from the cotton plant. Before the complete withdrawal from the pickers, the sharp incline ceases and a gradual incline occurs to the point E^8 . When the point E^8 is reached, the pickers are near the outward limit of their travel and are over the hopper G , (see Fig. 1). There is then a comparatively sharp incline to the point E^9 which causes the pickers to be entirely withdrawn in the wheel, and the cotton wound about them thus strikes the face of the wheel and is wiped off and falls into the hopper. It is then carried to a suitable receptacle by means of a conveyer G^1 or other mechanism, but as such mechanism is no part of my present invention I have not described it in detail. It will thus be seen that the pickers are thrust rapidly out into the cotton plant so as to be given a rapid rotation, that they then engage the cotton and it becomes wound about the pickers and is torn from the cotton bolls, and that these pickers are then rapidly withdrawn a portion of their length and are finally drawn within the wheel when they reach the top part thereof so as to wipe the cotton completely off.

When it is desired to throw the machine out of gear the guide piece F^1 may be loosened from its support and moved to one side as shown in dotted lines in Fig. 6. In this position it does not engage the rollers of the actuating piece and hence the machine can be moved from place to place without operating the pickers. The actuating parts E are arranged so as to resist lateral strain, as this is necessary to avoid cramping, because of the fact that these guides have to resist what may develop into a very heavy cramping strain at certain points of the circuit of travel, namely at the point where they make contact with the cotton plants. In order to secure this result I provide a flanged disk H which is mounted upon the axle A^1 and connected with the hub of the wheel so as to rotate therewith. The flange H^1 of this disk is provided with a series of grooves H^2 , (see Figs. 2, 3 and 12) of sufficient width to receive the actuating parts E . The actuating parts are located in these grooves and slide back and forth therein. It will thus be seen that they have a long bearing which takes up the lateral strain which becomes very great at every revolution of the wheel when the inclined part of the cam is reached. When it is desired to throw the device out of gear, the guiding piece F^1 is moved outwardly to the right, that is to the outer edge of the support F^3 .

This is done by loosening the screws by which it is fastened. When in this position it becomes inoperative and hence the pickers will not be moved by the rotation of the wheel.

Referring now to Figs. 7 and 11, inclusive, I have illustrated one form of guiding device for the spiral pickers. This device consists of a casing preferably square except at the end I which is round and screw-threaded. This casing may be cast and in such event the square or rectangular portion would be made with three sides integral, as shown in Fig. 9, while the other side I¹ is made separate and attached by means of screws I² or the like located at one end, the piece I¹ provided at the other end with one or more projections I³, see Fig. 10, which passes beneath the portion I so as to hold the side pieces in place. The casing is provided with a series of grooves I⁴, (see Fig. 7) located at proper intervals and a series of engaging pieces J are slipped into these guides before the side I¹ is added. These engaging pieces are provided with slots J¹ through which the spiral pickers pass and it is the engagement of the sides of the spiral pickers with the edges of these slots that causes the pickers to rotate when reciprocated. In this construction the metal at the two edges of the slot between its ends projects inwardly and are rounded, as shown in Figs. 7 and 11. These engaging pieces may also be cast if desired and the slots are provided at each end with enlargements J², the end portions of the slot being wider than the metal portion. By this construction the flexible picker points B² on the pickers pass through the enlarged ends of the slots and thus do not make frictional contact with the sides thereof, and wear and injury to such picker points is prevented. When the engaging pieces J are separated a distance equal to the pitch of the spiral, the slots are parallel, but if separated a distance only half this pitch one slot will be at right angles to the other, as shown for example at the left end of Fig. 7. Any number of these engaging devices that may be desired can be used in each guide. The enlarged engaging faces of the engaging devices at the edge of the slot may be case hardened if desired. The end piece I is provided with inclined faces I⁶ substantially uniform in width so that in case the picker is out of line with the slot I⁷ in the end thereof, it will be guided by these inclined faces so as to pass through the slot. Mounted upon the flange H¹ of the flanged disk H is a disk K to which is connected a series of braces K¹ connected at the other end to the overhanging periphery of the wheel. This flange and these braces brace the wheel and strengthen it and also act as supports for the guide rods along which the picker bars C move.

It will be noted that I have shown in the present cotton picking device a simple construction arranged to secure strength and durability. It will further be noted that the bars D are connected with the picker bars 70 and have a direct connection with the hub of the wheel.

I have described in detail a particular construction embodying my invention, but it is, of course, evident that the parts may be varied in many particulars and some of the parts omitted and others used with parts not here shown without departing from the spirit of my invention. I, therefore, do not limit myself to the particular construction 80 shown.

It will be noted that the guides C¹ extend across the wheel and engage the bars C at points between their ends, the bars C being guided by the guides C¹. The guides C¹, in addition to acting as guides, act to strengthen the wheel and keep the parts in proper position. This is an important feature in the construction of this device both in its operation and manufacture. It will further be noted that there are connected with each bar C a series of laterally projecting arms, to which pickers are connected. This is also an important feature, as it greatly increases the number of pickers and permits the proper position thereof so as to insure the pickers coming into contact with all of the bolls of the cotton plants.

I claim:

1. A wheeled cotton picking device comprising a picker, a reciprocating bar to which said picker is connected, a lever connected at one end to said bar and at the other end fulcrumed upon the hub of the wheel, and an actuating device for said lever. 100

2. A wheeled cotton picking device comprising a picker, a reciprocating bar to which said picker is connected, a lever connected at one end to said bar and at the other end fulcrumed upon the hub of the wheel, an actuating piece connected with said lever, means for reciprocating said actuating piece, and an extended guide-way in which 110 said actuating piece is received. 115

3. A cotton picking device comprising a rotatable wheel, a picker mounted thereon, a bar to which said picker is connected, a lever connected with said bar and pivoted to a part of said wheel, and means for rocking said lever about its pivotal point so as to 120 reciprocate the picker.

4. A cotton picking device comprising a reciprocating rotatable picker, a pivoted lever connected with the picker so as to move 125 it in the direction of its length and adapted to be rotated about an axis, an actuating part connected with said pivoted lever, a cam device for actuating said actuating part having a slot for said actuating part, and 130

- means for moving said cam device and actuating part relatively to reciprocate said actuating part to move said lever.
5. A cotton picking device comprising a wheel, an axle upon which it is mounted, a picker mounted on said wheel, an actuating mechanism therefor, comprising a reciprocating actuating part having a movement in the direction of its length, a groove in which said part works, a cam device fixed to the axle and a projection on the actuating part engaging said cam device whereby the actuating part is reciprocated when the wheel is rotated.
10. A cotton picking device comprising a wheel, an axle upon which said wheel is mounted, a picker carried by said wheel, an actuating mechanism for said picker comprising a cam device, a support upon which the cam device is carried, and to which the cam device is removably connected, said support adjustably mounted upon a non-rotatable part so that it may be adjusted to vary the position of the cam device.
15. A cotton picking device comprising a series of cotton pickers, a series of bars to which they are connected, an actuating mechanism associated with each cotton picker bar comprising a reciprocating, actuating part, a flanged disk connected so as to rotate with the wheel and provided with a series of slots extending through the flange thereof, said reciprocating, actuating parts working in said slots.
20. A cotton picking device comprising a reciprocating picker, a reciprocating bar connected with said picker at right angles thereto, a pivoted lever pivoted at one end to said bar and at the other end to a part of the machine, and an actuating part connected with said lever between its two pivoted parts so as to move it about its pivotal point.
25. A cotton picking machine comprising a picker, a guide through which the picker passes, an actuating piece for the picker, substantially parallel therewith, and an intermediate multiplying device connected with the picker and with the actuating piece for increasing or multiplying the motion of the actuating piece.
30. A cotton picking device comprising a wheel, a rotatable cotton picker mounted thereon, a movable part separated therefrom, and a movement multiplying device connecting the picker and the movable part.
35. A cotton picking device comprising a wheel, a cotton picker carried by said wheel and movable with relation to said wheel, a movable part rotating with the wheel and movable with relation thereto, and a multiplying device for multiplying the motion of the movable part, connecting the movable part with the picker.
40. A cotton picking device comprising a wheel, a picker mounted thereon, a movable part rotating with the wheel, a controlling device for said movable part, and a movement multiplying device connecting the movable part with the picker.
45. A cotton picking device comprising a wheel, a spiral cotton picker, a guide on the wheel through which said picker passes, said guide having means adapted to cause the picker to rotate when moving longitudinally, a movable actuating piece, and a movement multiplying device connecting said movable actuating piece with said picker.
50. A cotton picking device comprising a wheel, a spiral cotton picker, a guide on the wheel through which said picker passes, said guide having means adapted to cause the picker to rotate when moving longitudinally, a movable actuating piece, and a movement multiplying device connecting said movable actuating piece with said picker.
55. A cotton picking device comprising a wheel, a series of cotton pickers rotating with the wheel, a bar to which said cotton pickers are connected, an actuating part, and a movement multiplying device between said actuating part and said bar.
60. A cotton picking device comprising a wheel, a series of pickers mounted thereon, a bar to which said pickers are connected, an actuating piece actuating with said bar, a movement multiplying device connecting said actuating piece and said bar, an engaging device on said actuating piece, and a controlling cam associated with the axle of the wheel engaged by said engaging device.
65. A cotton picking device comprising a wheel, a series of cotton pickers rotating therewith, a bar to which said pickers are attached, a rocking lever attached to said bar, an actuating device for said lever, and means for moving said actuating device with relation to said wheel when the wheel is rotated.
70. A cotton picking device comprising a wheel, a series of spiral cotton pickers mounted thereon, a series of guides carried by said wheel through which said pickers pass, said guides having means adapted to rotate the pickers when they are reciprocated, a bar to which said pickers are rotatably attached, a rocking lever attached to said bar, and means for moving said lever when the pickers reach a predetermined point, so as to rapidly thrust them through the guides.
75. A cotton picking device comprising a wheel, a series of spiral cotton pickers mounted thereon, a series of guides carried by said wheel through which said pickers pass, said guides having means adapted to rotate the pickers when they are reciprocated, a bar to which said pickers are rotatably attached, a rocking lever attached to said bar, and means for moving said lever when the pickers reach a predetermined point, so as to rapidly thrust them through the guides.
80. A cotton picking device comprising a wheel, a series of cotton pickers rotating with the wheel, a bar to which said pickers are connected, an actuating part, and a movement multiplying device between said actuating part and said bar.
85. A cotton picking device comprising a wheel, a series of pickers mounted thereon, a bar to which said pickers are connected, an actuating piece actuating with said bar, a movement multiplying device connecting said actuating piece and said bar, an engaging device on said actuating piece, and a controlling cam associated with the axle of the wheel engaged by said engaging device.
90. A cotton picking device comprising a wheel, a series of cotton pickers rotating with the wheel, a bar to which said pickers are attached, a rocking lever attached to said bar, an actuating device for said lever, and means for moving said actuating device with relation to said wheel when the wheel is rotated.
95. A cotton picking device comprising a wheel, a series of spiral cotton pickers mounted thereon, a series of guides carried by said wheel through which said pickers pass, said guides having means adapted to rotate the pickers when they are reciprocated, a bar to which said pickers are rotatably attached, a rocking lever attached to said bar, and means for moving said lever when the pickers reach a predetermined point, so as to rapidly thrust them through the guides.
100. A cotton picking device comprising a wheel, a series of spiral cotton pickers mounted thereon, a series of guides carried by said wheel through which said pickers pass, said guides having means adapted to rotate the pickers when they are reciprocated, a bar to which said pickers are rotatably attached, a rocking lever attached to said bar, and means for moving said lever when the pickers reach a predetermined point, so as to rapidly thrust them through the guides.
105. A cotton picking device comprising a wheel, a series of spiral cotton pickers mounted thereon, a series of guides carried by said wheel through which said pickers pass, said guides having means adapted to rotate the pickers when they are reciprocated, a bar to which said pickers are rotatably attached, a rocking lever attached to said bar, and means for moving said lever when the pickers reach a predetermined point, so as to rapidly thrust them through the guides.
110. A cotton picking device comprising a wheel, a series of spiral cotton pickers mounted thereon, a series of guides carried by said wheel through which said pickers pass, said guides having means adapted to rotate the pickers when they are reciprocated, a bar to which said pickers are rotatably attached, a rocking lever attached to said bar, and means for moving said lever when the pickers reach a predetermined point, so as to rapidly thrust them through the guides.
115. A cotton picking device comprising a wheel, a series of spiral cotton pickers mounted thereon, a series of guides carried by said wheel through which said pickers pass, said guides having means adapted to rotate the pickers when they are reciprocated, a bar to which said pickers are rotatably attached, a rocking lever attached to said bar, and means for moving said lever when the pickers reach a predetermined point, so as to rapidly thrust them through the guides.
120. A cotton picking device comprising a wheel, a series of spiral cotton pickers mounted thereon, a series of guides carried by said wheel through which said pickers pass, said guides having means adapted to rotate the pickers when they are reciprocated, a bar to which said pickers are rotatably attached, a rocking lever attached to said bar, and means for moving said lever when the pickers reach a predetermined point, so as to rapidly thrust them through the guides.
125. A cotton picking device comprising a wheel, a series of cotton pickers, a cam on the axle of said wheel, and comprising a central part with two separated cam rings mounted thereon side by side and adapted

to be moved relatively so as to vary the width of the slot between them, a movable piece provided with an engaging device adapted to pass between the cam rings, and a connection between said movable part and said pickers.

20. A cotton picking device comprising a wheel, a series of pickers mounted thereon, a series of bars to which said pickers are connected, a rocking lever connected with each of said bars, a movable device connected with each of said rocking levers, the said bars projecting between the said rocking levers in proximity with the hub of the wheel.

21. A cotton picking device comprising a wheel, a series of pickers mounted thereon, a series of bars to which said pickers are connected, said bars provided with a series of laterally projecting arms, each carrying a picker, actuating mechanism for moving said bars back and forth, and a multiplying device associated with said actuating mechanism.

22. A cotton picking device comprising a wheel, a reciprocating picker mounted thereon, a multiplying actuating device connected at one end with said picker and at the other end with a driving part associated with the device.

23. A cotton picking device comprising a wheel, a picker mounted thereon and rotating with the wheel, means for moving the picker and for rapidly thrusting it out into the cotton plant when the wheel reaches a predetermined position, and means including a multiplying device for multiplying the movement thereof.

24. A cotton picking device comprising a wheel, a series of pickers mounted thereon and rotating with the wheel, bars with which said pickers are connected and guides extending across the wheel and engaging said bars between their ends. 40

25. A cotton picking device comprising a wheel, a series of pickers mounted thereon and rotating with the wheel, bars with which said pickers are connected and guides extending across the wheel and engaging said bars between their ends, arms connected with said bars between the points 45 60 where they engage said guides and means for moving said arms to reciprocate the pickers.

26. A cotton picking device comprising a wheel and series of picker bars mounted on 55 said wheel and adapted to be moved back and forth, a series of pickers connected with said bars and a series of laterally projecting arms connected with said bars, and pickers connected with said laterally projecting 60 arms.

27. A cotton picking device comprising a wheel and series of picker bars mounted on said wheel and adapted to be moved back and forth, a series of pickers connected with 65 said bars and a series of laterally projecting arms connected with said bars, and pickers connected with said laterally projecting arms, said laterally projecting arms projecting at various angles from said bars.

NATHANIEL BOWDITCH.
